AIR CONDITIONING SYSTEM

George D. Guler, Philadelphia, Pa., assignor to
Minneapolis-Honeywell Regulator Company,
Minneapolis, Minn., a corporation of Delaware

Application February 6, 1937, Serial No. 124,459

19 Claims. (Cl. 62—6)

This invention relates in general to the art of air conditioning and is more particularly concerned with the cooling and dehumidification of air.

The primary object of my invention is to provide an air conditioning control system which is relatively simple in operation and which acts to automatically maintain the temperature and humidity of the air in a space within predetermined limits, such system being also adapted to meet sudden changes in refrigeration load.

In order to reduce excessive temperature or humidity, removal of heat from the air is necessary. Reduction in humidity however, requires a different type of cooling action than does reduction of temperature. In order to reduce the temperature of air it is necessary only to remove sensible heat from the air and to remove part of the superheat of the water vapor contained in the air. For reducing humidity however, it is necessary to remove moisture from the air, this requiring first that the temperature of the air be reduced to the dew-point. Upon removal of heat from the air after the dew-point temperature has been reached, condensation of moisture and consequent dehumidification will occur.

When air is passed over a cooling coil or other type of cooling element both temperature reduction and dehumidification may occur. The proportion of the refrigeration effect of such coil going towards dehumidification and the proportion of such refrigeration effect which acts to cool or reduce temperature will depend upon temperature of the coil and the dew-point temperature of the air. By varying the coil temperature the ratio of cooling to dehumidifying may be varied. For instance, as the coil temperature is maintained above the dew-point temperature of the air, the air temperature cannot be reduced below its dew-point. Thus, for this coil condition there will be no dehumidifying action whatsoever and the total refrigeration effect of the coil will go towards temperature reduction or cooling of the air. If, however, the coil temperature is reduced below the dew-point of the air, both a cooling and dehumidifying action will occur, the cooling coil acting first to reduce the air temperature to the dew-point and then to condense moisture in the air. Inasmuch as the dehumidifying action of the coil increases at a faster rate as the cooling coil temperature is reduced below the dew-point, than the corresponding increase in cooling effect, the dehumidifying action may be increased without corresponding increase in cooling effect by re-

ducing the coil temperature below the dew-point.

In accordance with my invention I make use of the above mentioned principles of operation. In a preferred embodiment of my invention I employ a plurality of cooling coils or elements in a single conditioning chamber, these coils being connected together to a common refrigeration system, each system comprising a battery of compressors. Each cooling coil is provided with a control valve at its inlet, these valves acting to prevent or permit flow of refrigerant into their respective evaporators. A temperature control system is employed which acts to progressively open these valves as the temperature of the air within the space increases above a predetermined value. This temperature control means is arranged also to progressively place the compressors in operation, that is, each time that a valve is opened by the temperature control device, a compressor is likewise placed into operation. By placing these cooling coils in operation as the temperature increases, the cooling area over which the air is passed is increased to meet this increase in cooling load. Due to the fact that a compressor is placed into operation simultaneously with each cooling coil, the temperature of all the cooling coils will remain unchanged regardless of the number of cooling coils in operation. This temperature is selected to cause both a cooling and dehumidifying action on the air. In order to prevent the humidity of the air from falling below a predetermined value, a humidostat is located within the space to be conditioned, this humidostat being arranged to open all of the solenoid valves when the humidity falls below a predetermined value. Due to this opening of all the valves, all of the cooling elements will be placed into operation. As the number of compressors in operation is unchanged, this results (if less than the total number of compressors are in operation) in a rising of pressure within the cooling coils with the consequent rising in temperature of such coils. This causes the temperature of the coils to rise above the dew-point of the air thus stopping all dehumidifying action and causing the entire cooling effect of the system to go towards sensible heat reduction. This control arrangement therefore forms one object of my invention.

50 A further object of my invention is to provide an air conditioning system for cooling and dehumidifying air, such system including control devices for varying the temperature and effective area of cooling elements in accordance with temperature and humidity conditions.

A further object of my invention is to provide an air conditioning system having a plurality of cooling elements connected in multiple to a common refrigerant supply means, with control means for sequentially placing said cooling elements into and out of operation and for substantially simultaneously changing the operation of the refrigerant supply means in accordance with a predetermined schedule.

Another object of my invention is the provision of an air conditioning system having a plurality of cooling elements connected to a common refrigerant supply system, with temperature and humidity responsive means for controlling the cooling elements and the refrigerant supply system in a manner to maintain the desired temperature and humidity conditions.

A still further object is the provision of novel control means for a refrigeration system of the type employing a plurality of cooling elements connected to a common refrigerant supply means, such control means acting to vary both the number of cooling elements in operation and the operation of the refrigerant supply means in a manner to maintain desired temperature and humidity conditions within a conditioned space.

Another object of my invention is the provision of a refrigeration system having a group of cooling coils connected to a group of compressors, such system having a temperature responsive means for sequentially placing said cooling coils and compressors into operation and having a humidity responsive means for dominating part of the action of said temperature responsive means.

Further objects will appear from the following specification and the appended claims.

For a full understanding of my invention, reference is made to the following specification and to the accompanying drawing, the single figure of which illustrates diagrammatically one form which my invention may take.

Reference character 1 indicates a conditioning chamber provided with an inlet duct 2 communicating with a space to be conditioned 3. Conditioning chamber 1 at its opposite or outlet end 4 is connected to a fan 5 the discharge side of which is connected to the delivery duct 6 which leads to the space 3. Located in conditioning chamber 1 are a series of cooling coils or elements 7, 8, 9 and 10. These cooling coils are connected by suitable branch pipes to a discharge header 11, this header being connected by a suitable conduit 12 to a second header 13. Connected to the header 13 are branch pipes 14, 15, 16 and 17 which lead to the suction sides of compressors 18, 19, 20 and 21 respectively. In this manner the battery of cooling coils 7, 8, 9 and 10 is connected as a unit to the battery of compressors 18, 19, 20 and 21. Connected to the discharge sides of compressors 18, 19, 20 and 21 are branch pipes 22, 23, 24 and 25 these branch pipes leading to a pump discharge header 26. Header 26 is in turn connected to the inlet of a suitable condenser 27, the outlet of this condenser being connected by a pipe 28 to a supply header 29. Supply header 29 is connected by branch conduits 30, 31, 32 and 33 to the inlets of cooling elements 7, 8, 9 and 10 respectively. Interposed in each of the branch conduits 30, 31, 32 and 33 are solenoid flow controlling valves 34, 35, 36 and 37. These solenoid valves are preferably of the type which open when energized and which close when deenergized. Also located in the branch pipes 30, 31, 32 and 33 are suitable ex-

pansion valves 38, 39, 40 and 41. From the foregoing it should be apparent that the battery of cooling elements 7, 8, 9 and 10 are connected in multiple to a battery of compressors 18, 19, 20 and 21, these compressors discharging into a common condenser from which liquid refrigerant is supplied to the cooling elements.

The operation of the refrigeration system above described is identical with that of an ordinary compression refrigeration system. The compressors reduce the pressure within the cooling coils, thus causing the liquid refrigerant therein to evaporate and absorb heat. This evaporating refrigerant is raised in pressure by the compressors and supplied to the condenser wherein heat is removed causing the refrigerant to condense to the liquid state. This liquid refrigerant is then supplied through the solenoid valves and the expansion valves to the various cooling elements. As the refrigerant passes through the expansion valves its pressure is greatly reduced, this sharp reduction in pressure permitting evaporation of the liquid refrigerant at a low temperature, thus causing heat to be absorbed from the air by the various cooling elements. The evaporated refrigerant is then returned to the compressor and the cycle repeated continuously.

Reference character 45 indicates generally a thermostatic controller. This controller comprises an expansible and contractable bellows 46 which is connected by a capillary tube 47 to a suitable control bulb 48 which may be located in the return air duct 2. The bellows 46, tube 47 and bulb 48 are filled with a suitable volatile substance as well known in the art. As the temperature within the return air duct 2 falls, the vapor pressure of the volatile fill will decrease, thus causing contraction of the bellows 46. Conversely upon an increase in temperature within the return air duct 2, the vapor pressure within the bulb, tube and bellows will increase, thus causing expansion of the bellows 46. Cooperating with the bellows 46 is a bell-crank lever pivoted at 49 and having an actuating arm 50 and a control arm 51. Actuating arm 50 abuts against the bellows 46 and is urged thereagainst by a spring 52 which is connected to a suitable fixed member 53. The control arm 51 cooperates with a control resistance 54 to form a potentiometer. The controller just described is herein illustrated as being so designed and adjusted that when the return air temperature is 75° F., the control arm 51 will just engage the extreme left end of resistance 54. As the return air temperature increases, arm 51 will move to the right, and when the return air temperature increases to 77° F., the arm 51 will engage the extreme right hand end of control resistance 54. The control arm 51 and the ends of the control resistance 54 are connected to a proportioning motor generally indicated at 55. This proportioning motor may be of the type illustrated in Patent 1,989,972 issued to Lewis L. Cunningham on February 5, 1935. This type proportioning motor is adapted to rotate a shaft 56 to angular positions corresponding with the position of the control arm 51 on the control resistance 54. In other words, for each position of the control arm 51 on the control resistance 54 there will be a corresponding angular position of the shaft 56.

Located on the shaft 56 are a series of cams 57, 58, 59 and 60, the raised portion of these cams being angularly displaced from one another. Cooperating with the cams 57, 58, 59 and 60 are

cam followers 61, 62, 63 and 64, these cam followers having mounted thereon mercury switches 65, 66, 67 and 68 respectively. Referring again to the proportioning motor 55, this motor is arranged to rotate shaft 56 in a counterclockwise direction as the control arm 51 of controller 45 moves across the control resistance 54 from left to right or in other words upon an increase in return air temperature. It will be observed that cams 57, 58, 59 and 60 are provided with raised portions and recessed portions. The cam 51 is positioned on shaft 56 so that the recessed portion thereof will engage the cam follower for the angular position of the shaft 56 occurring when control arm 51 engages the extreme left-hand end of the control resistance 54. (75° F.) When, however, control arm 51 is moved from the extreme end of control resistance 54, the shaft 56 will be rotated counter-clockwise, thus bringing the raised portion of the cam into engagement with the cam follower, this causing tilting of the mercury switch 65 to closed position. The raised portion of cam 58 is angularly displaced in a clockwise direction from that of the cam 57. Thus before the raised portion of cam 58 will engage the cam follower 62, shaft 56 must be rotated further in a counter-clockwise direction, this action occurring only when control arm 51 is moved further across control resistance 54. Similarly the raised portion of cam 59 is angularly displaced in a clockwise direction from that of the cam 58 and the raised portion of cam 60 is displaced in a clockwise direction from that of the cam 59. It should be apparent therefore, that as the shaft 56 is rotated in a counter-clockwise direction under the control of controller 45 the mercury switch 65 will first be tilted to closed position. Upon further rotation the mercury switch 66 will be tilted toward closed position and upon still further rotation the mercury switch 67 and the mercury switch 68 will be sequentially tilted to closed position. Conversely as the shaft 56 is rotated in a clockwise direction the mercury switches will be tilted to open position in reverse order. It should now be apparent that when the return air is relatively cool, the control arm 51 will engage the extreme left-hand of control resistance 54, thus causing rotation of shaft 56 to a position to which all of the mercury switches are in open position. As the temperature of the return air increases however, the control arm 51 will move across control resistance 54 from left to right, thus causing counter-clockwise rotation of shaft 56 and tilting of mercury switch 65 to closed position. Upon further increase in temperature shaft 56 will be rotated further in a counter-clockwise direction causing progressively tilting of mercury switches 66, 67 and 68 to closed position. The mercury switches therefore are operated sequentially and the number of mercury switches tilted to closed position is dependent upon the temperature of the return air.

Reference characters 70 and 71 indicate suitable line wires. One electrode of each of the mercury switches 65, 66, 67 and 68 are connected by wires 72, 73, 74 and 75 to the line wire 71. Another electrode of mercury switch 65 is connected by wire 76 to one terminal of the control box 77 for the compressor 18. In a similar manner the mercury switches 66, 67, and 68 are connected to the compressor control boxes 78, 79 and 80 by wires 81, 82 and 83 respectively. The other terminals of control boxes 77, 78, 79 and 80 are connected by means of wires 84, 85 86 and 87

to the line wire 70. It should thus be apparent that the control boxes 77, 78, 79 and 80 are connected across the line wires 70 and 71 in series with the mercury switches 65, 66, 67 and 68 respectively.

5 The center electrode of the mercury switch 65 is connected by wire 88 to one terminal of the solenoid valve 34. In a similar manner electrodes of mercury switches 66, 67 and 68 are connected respectively to the solenoid valves 35, 36 and 37 by wires 89, 90 and 91 respectively. The other terminals of the solenoid valves 34, 35, 36 and 37 are connected together and to line wire 70 by wires 92, 93, 94, 95 and 96. The control valves 34, 35, 36 and 37 are therefore connected across the line wires 70 and 71 in series respectively with mercury switches 65, 66, 67 and 68.

10 From the foregoing it should be apparent that each of the mercury switches 65 to 68 controls both a solenoid valve and a compressor starter. For instance, when the mercury switch 65 is tilted to closed position the solenoid valve 34 will be energized by a circuit as follows: line wire 71, wire 72, mercury switch 65, wire 88, solenoid valve 34, wire 92, and wire 93 to line wire 70. Also the compressor starter 77 for the compressor 18 will be energized as follows: line wire 71, wire 72, mercury switch 65, wire 76, compressor starter 77, wire 84, and wire 87 to line wire 70. In a 15 similar manner closure of mercury switch 66 opens solenoid valve 35 and starts the compressors 19, and closure of mercury switches 67 and 68 causes opening of solenoid valves 36 and 37 and starting of the compressors 20 and 21. It should 20 now be apparent that the number of cooling coils and compressors placed in operation is dependent upon return air temperature. In other words, when the return air temperature is below a pre-determined value, for instance 75 degrees, the 25 control arm 41 of the temperature controller 45 will engage the extreme left-hand portion of control resistance 54, this causing the proportioning motor 55 to rotate shaft 56 to a position in which all of the mercury switches are in open position. As the temperature of the return air increases the proportioning motor will rotate shaft 56 in a manner hereinbefore described to tilt mercury switch 65 to closed position, this causing opening of solenoid valve 34 and starting of the compressor 18. As the temperature continues to rise shaft 56 will be rotated further, this causing tilting of the mercury switch 66, this in turn causing opening of the solenoid valve 35 and starting of the compressor 19. In a 30 similar manner as the return air temperature increases further, the mercury switches 67 and 68 will be sequentially moved to closed position, this causing sequential opening of solenoid valve 36 and starting of compressor 20 and opening of solenoid valve 37 and starting of compressor 21. Under a rising temperature, therefore, the 35 number of cooling elements and compressors in operation is sequentially increased.

40 In the drawing, I have illustrated the compressors as being of equal size, and the cooling coils 7, 8, 9 and 10 as progressively increasing in size. The reason for this variation in size of the cooling coils is that the temperature difference between the air being cooled and the cooling coils decreases progressively as the air passes over the coils. Hence the effectiveness of the cooling surface of the cooling coils 7, 8, 9 and 10 progressively decreases. By progressively increasing the size of said coils as shown, the cooling effect of each coil may be made equal. As

the compressors are of equal size, and the cooling effect of each coil is equal, it will be apparent that when an additional coil and compressor are placed in operation in the manner above described, the increase in load caused by the additional cooling coil will be just carried by the additional compressor, and hence the pressure in the cooling coils in operation will not be affected. While I have shown the coils of being of varying size and the compressors as being of equal size, it will be apparent that if desired, the coils may be made of equal size and the compressor capacities varied correspondingly. The important feature is that the capacities of the compressors be approximately equal to the cooling effect of their corresponding cooling coils. It will be apparent however that my invention is not limited to this feature.

Located in the conditioned space 3 is a humidity controller generally indicated at 100. This controller comprises a mercury switch carrier 101 which is pivoted at one end and which carries a mercury switch 102. To the free end of element 101 is connected a spring 103 which is in turn connected to a suitable fixed member 104. Also connected to the free end of element 101 is a humidity responsive device, this device comprising of a plurality of strands 105 of moisture responsive material, these strands being secured to clamping members 106 and 107, the clamping member 106 being secured to the switch carrier 101 and the clamping member 107 being secured to a suitable fixed support. As the humidity within the space increases, the strands 105 will increase in length thereby permitting the spring 103 to tilt the switch carrier 101 in a clockwise direction, thereby tilting mercury switch 102 to open position. When the humidity decreases however, the strands 105 will decrease in length thus rotating switch carrier 101 in a counter-clockwise direction against the action of spring 103. When the humidity falls to a predetermined value such as 50% the shrinking of strands 105 will be sufficient to cause the mercury switch 102 to be tilted to closed position.

Reference character 110 indicates generally a relay controlled by the humidostat 100. This relay comprises a plurality of switch arms 111, 112, 113 and 114 arranged to cooperate with contacts 115, 116, 117 and 118 respectively. These switch arms are connected to a suitable plunger located within the magnetic field of relay coil 119. When relay coil 119 is energized the plunger is moved to the right thereby moving switch arms 111, 112, 113 and 114 into engagement with their respective contacts. When, however, the relay coil 119 is deenergized, the switch arms are moved away from their contacts by means of gravity or springs (not shown). The switch arms 111 to 114 are connected by wires 120 and 121 to the line wire 71. The contacts 115, 116, 117 and 118 are connected respectively by wires 122, 123, 124 and 125 to the wires 88, 89, 90 and 91 and in this manner are connected to the solenoid valves 34, 35, 36 and 37 respectively. One end of the relay coil 119 is connected to line wire 71 by means of wire 121, and the other end of coil 119 is connected by wire 126 to the mercury switch 102 of the humidity controller 100, the other electrode of said mercury switch 102 being connected by wire 127 to the line wire 70.

The function of the humidity controller 100 and the relay 110 is to cause opening of all of the

solenoid valves whenever the humidity within the conditioned space falls below a predetermined value. So long as the humidity within the space 3 is above such predetermined value 5 the mercury switch 102 will be tilted to open position thereby deenergizing the coil 119 of relay 110. Upon falling of the humidity to the predetermined value, the mercury switch 102 will be tilted to closed position this energizing relay 10 coil 119 by a circuit as follows: line wire 70, wire 127, mercury switch 102, wire 126, relay coil 119 and wire 121 to line wire 71. Energization of relay coil 119 will cause the switch arms 111 to 114 to engage their respective contacts 115 to 118. Engagement of switch arm 111 with the contact 115 will energize the solenoid valve 34 by a circuit as follows: line wire 71, wire 121, wire 120, switch arm 111, contact 115, wire 122, wire 88, solenoid valve 34, wire 92, and wire 93 to line wire 70. In a similar manner engagement of switch arm 112 with contact 116 will energize the solenoid valve 35, and engagement of switch arms 113 and 114 with their respective contacts, 117 and 118, will cause energization of the respective solenoid valves 36 and 37. It should therefore be seen that when the humidity within the space 3 is below a predetermined value, the solenoid valves 34, 35, 36 and 37 will be opened independently of the action of the mercury switches 65, 66, 67 and 68. The energization of relay 110 while causing opening of all the solenoid valves however has no effect upon the number of compressors in operation. In other words, the number of compressors 20 placed in operation is controlled entirely by the temperature controller 45, while the number of cooling coils placed in operation is controlled by the temperature controller so long as the humidity within the space is above a predetermined value. When, however, the humidity falls below such value, all of the solenoid valves will be opened regardless of the action of the temperature controller.

Operation

45 In practicing my invention the capacities of the compressors will be made sufficiently high to enable one compressor to reduce the temperature of one coil below the dew-point of the air passing thereover. The capacities however are preferably not great enough to enable one compressor to reduce the temperature of more than one coil substantially below the dew-point of the air. Therefore, with one compressor and one coil in operation, the temperature of the coil will be below the dew-point of the air thereby causing the coil to have both a dehumidifying and a cooling action. Similarly if two compressors and two coils are in operation the temperature of both coils will be below the dew-point of the air and as long as the same number of compressors and coils are in operation, the temperature of the coils will remain below the dew-point. If, however, all of the coils are placed in operation, and but part of the compressors are operating, the temperature of the coils will be above the dew-point, thereby causing the coils to have only a cooling action.

With the parts in the position shown the return air temperature is about 76 degrees as indicated by the control arm 51 of temperature controller 45 engaging the mid portion of control resistance 54. Under this temperature condition the proportioning motor 55 has rotated the shaft 56 to the position shown in which the

mercury switches 65 and 66 are in closed position. The cooling coils 7 and 8 and their corresponding compressors 18 and 19 are therefore in operation. Also the humidity within the space 3 is above 50% as indicated by the mercury switch 102 of humidity controller 100 being tilted to open position. The relay coil 119 is therefore deenergized and the switch arms 111 to 114 are disengaged from their contacts 115 to 118. Under these conditions the control of the number of coils and compressors in operation is accomplished entirely by the temperature controller. As the number of cooling coils and compressors in operation are equal, the temperature of the two cooling coils in operation is below the dew-point and therefore both reduction in temperature and reduction in humidity is being effected.

Should the return air temperature fall, the control arm 51 of the temperature controller will be rotated in a counter-clockwise direction, this causing rotation of the proportioning motor shaft 56 in a clockwise direction which will ultimately result in tilting of the mercury switch 66 to open position, this in turn causing closing of the solenoid valve 35 and stopping of its corresponding compressor 19. Should the temperature continue to fall the proportioning motor shaft 56 will be further rotated in a clockwise direction this tilting mercury switch 65 to open position causing closing of solenoid valve 34 and stopping of compressor 18. Therefore, when the temperature is lowered to a predetermined value (in this case 75° F.), all of the cooling coils and all of the compressors will be placed out of operation thus preventing further reduction in temperature regardless of what the prevailing humidity may be.

If, however, the temperature of the return air should increase, the proportioning motor shaft will be rotated in the opposite direction, this causing sequential opening of the mercury switches 65, 66, 67 and 68. In other words, as the return air temperature increases first one cooling coil and one compressor will be placed in operation. As the return air temperature increases further, a second cooling coil and a second compressor will be placed in operation. Similarly upon further increase in temperature a third cooling coil and compressor and a fourth cooling coil and compressor will sequentially be placed in operation. As the number of compressors in operation will under this mode of control remain equal to the number of cooling coils in operation, regardless of what the air temperature may be, the temperature of whatever number of cooling coils is placed in operation will remain below the dew-point of the air this causing the cooling coils to both remove sensible heat from the air and dehumidify the air. In other words, so long as the humidity remains above 50% the number of cooling coils placed in operation will be dependent only upon the temperature of the return air, the number of cooling coils being progressively increased as the return air temperature increases and being progressively decreased as the return air temperature decreases. Due to the fact that the number of compressors in operation is varied simultaneously with the number of cooling coils, the temperature of the cooling coils in operation will remain substantially constant.

So long as the humidity of the space 3 is above the predetermined value, the cooling coils in operation will act to both cool and dehumidify the air. The operation of the cooling coils there-

fore will cause the humidity within the space to gradually decrease, this action causing the mercury switch 102 to be tilted towards closed position. When the humidity falls to a predetermined value, for instance 50%, the mercury switch 102 will be tilted sufficiently to cause closure thereof, this in the manner previously described, causing opening of all of the solenoid valves. If now, less than the total number of cooling coils and compressors had been placed in operation by the temperature controller, the opening of all solenoid valves will have the effect of placing a greater refrigeration load upon the compressors then in operation. The result of this increase in load upon the compressors will be a rise in pressure within the evaporators, this causing the temperature of the evaporators to rise correspondingly. As hereinbefore mentioned this rise in temperature will be sufficient to cause the temperature of the cooling coils to be above the dew-point of the air. Due to this rise in temperature of the cooling coils there will be no further dehumidifying action, and the entire refrigerating action of the coils will go towards reducing only the temperature of the air being conditioned. At this time it will be noted all of the cooling coils are in operation and hence the cooling surface is at a maximum. The effect of the humidity controller 100, therefore, is to increase the cooling area and to increase the temperature of the cooling coils whenever the humidity falls below a predetermined value, this resulting in shifting of the cooling effect of the coils to cause a maximum of sensible heat removal and a minimum of latent heat removal.

From the foregoing it should be apparent that I have disclosed an air conditioning control system which acts to maintain the temperature and humidity of the air below desired values, this system acting to increase the cooling coil surface as the temperature within the conditioned space increases thereby increasing the cooling effect as needed to maintain the space temperature within the desired limits. It should further be apparent that the temperature controller will place the same number of compressors in operation as the number of cooling coils, this causing both the cooling and dehumidifying action to be increased as the space temperature increases, this action occurring so long as the humidity within the space is above a predetermined value. When, however, the humidity falls below such predetermined value, all of the cooling coils are placed in operation, thus causing increase in temperature of the cooling coils thus decreasing the dehumidifying action of such coils while increasing the temperature reducing or cooling action.

While for purposes of description I have assumed certain values of temperature and humidity as the control points of the temperature and humidity controllers, it will be obvious that these values may be varied as desired. Also, while I prefer to proportion the cooling coil and compressor capacities so that the temperature of the cooling coils will be above the dew-point of the air when less compressors are in operation than cooling coils, I do not wish to be limited to this as it will be apparent that even though the cooling coil temperature is below the dew-point of the air under this condition, there would be less dehumidifying action than would occur were the number of coils and compressors in operation equal. Furthermore, while I prefer to obtain a variable refrigeration action by employing a plu-

rality of compressors and varying the number of compressors in operation, it is to be understood that my invention is not limited to this. For instance, if desired, a single compressor may be employed, and its output may be varied by varying its speed or by means of by-pass arrangements. Also, it will be apparent that my invention is not limited to a multiple evaporator compression refrigeration system, but is also applicable with other types of cooling apparatus. It will be apparent that many other changes which are within the scope of my invention will suggest themselves to those skilled in the art. I therefore desire to be limited only by the scope of the appended claims and the prior art.

I claim as my invention:

1. In an air conditioning system, in combination, a conditioning chamber, means connecting said conditioning chamber with a space to be conditioned, cooling means in said chamber, means for supplying cooling fluid to said cooling means, control means for gradually varying the flow of cooling fluid through said cooling means, control means for gradually varying the operation of said cooling fluid supplying means, and temperature and humidity responsive means for controlling said control means, one of said responsive means being arranged to control gradually both of said control means, and the other of said responsive means being arranged to cooperate in controlling one only of said control means.

2. In an air conditioning system, in combination, a conditioning chamber, means connecting said conditioning chamber with a space to be conditioned, a plurality of cooling devices in said chamber, common means for supplying cooling fluid to said devices, sequential control means for sequentially placing said cooling devices into or out of operative relationship with said cooling fluid supplying means substantially simultaneously with varying said cooling fluid supplying means, temperature responsive means for actuating said sequential control means, and humidity responsive means or placing said cooling devices into operative relationship with said cooling fluid supplying means independently of said sequential control means.

3. In an air conditioning system, in combination, a conditioning chamber, means connecting said conditioning chamber with a space to be conditioned, a plurality of cooling elements in said chamber, common means for supplying cooling fluid to said elements, flow control means for controlling the flow of cooling fluid into said elements, supply control means for said cooling fluid supply, a controller for actuating said flow control means in a manner to sequentially place said cooling elements into or out of operation, said controller being also arranged to control said supply control means to change the cooling fluid supply substantially simultaneously with changing the number of cooling elements in operation, and temperature and humidity responsive means, one of said responsive means being arranged to actuate said controller, and the other of said responsive means being arranged to cooperate with said controller in controlling one only of said control means.

4. In an air conditioning system, in combination, a conditioning chamber, means connecting said conditioning chamber with a space to be conditioned, a plurality of cooling elements in said chamber, a plurality of cooling fluid circulating devices, said circulating devices being

connected as a group to a group of said cooling elements, flow control means for controlling the flow of cooling fluid into said elements, control means for said cooling fluid circulating devices, a controller for actuating said flow control means in a manner to sequentially place said cooling elements into or out of operation, said controller being also arranged to actuate said circulating device control means to sequentially place said circulating devices into or out of operation, and temperature and humidity responsive means, one of said responsive means being arranged to actuate said controller, and the other of said responsive means being arranged to cooperate with said controller in controlling one only of said control means.

5. In an air conditioning system, in combination, a conditioning chamber, means connecting said conditioning chamber with a space to be conditioned, direct expansion cooling means in said chamber, means for supplying refrigerant to said cooling means, a back pressure reducing means connected to said cooling means, control means for gradually varying the flow of refrigerant to said cooling means substantially simultaneously with gradually changing the operation of said back pressure reducing means, temperature responsive means in control of said control means, and humidity responsiveness means arranged to cooperate with said control means in controlling the flow of refrigerant into said cooling devices only.

6. In an air conditioning system, in combination, a conditioning chamber, means connecting said conditioning chamber with a space to be conditioned, direct expansion cooling means in said chamber, means for supplying refrigerant to said cooling means, back pressure reducing means for said cooling means, control means for gradually controlling the flow of refrigerant into said cooling means, control means for gradually controlling said back pressure reducing means, and temperature and humidity responsive means for controlling said control means, one of said responsive means being arranged to control gradually both of said control means and the other of said responsive means being arranged to cooperate in controlling one only of said control means.

7. In an air conditioning system, in combination, a conditioning chamber, means connecting said conditioning chamber with a space to be conditioned, a plurality of direct expansion cooling devices in said chamber, means for supplying refrigerant to said cooling devices, common back pressure reducing means for said cooling devices, control means for sequentially preventing or permitting flow of refrigerant into said cooling devices, control means for gradually controlling said back pressure reducing means, and temperature and humidity responsive means for controlling said control means, one of said responsive means being arranged to control both of said control means and the other of said responsive means being arranged to cooperate in controlling one only of said control means.

8. In an air conditioning system, in combination, a conditioning chamber, means connecting said conditioning chamber with a space to be conditioned, a plurality of direct expansion cooling devices in said chamber, means for supplying refrigerant to said cooling devices, common back pressure reducing means for said cooling devices, control means for sequentially preventing or permitting flow of refrigerant into said cooling de-

5 vices, control means for gradually controlling said back pressure reducing means, temperature responsive means for controlling both of said control means, and humidity responsive means arranged to cooperate with said temperature responsive means in controlling the flow of refrigerant into said cooling devices only.

9. In a system of the class described, in combination, a cooling means, means for supplying cooling fluid to said cooling means, control means for gradually controlling the flow of cooling fluid, control means for gradually controlling the operation of said cooling fluid supplying means, a controller for gradually actuating both of said control means, and a second controller for actuating one only of said control means.

10. In an air conditioning system, in combination, a conditioning chamber, means connecting said conditioning chamber with a space to be conditioned, cooling means in said chamber, variable capacity means for supplying cooling fluid to said cooling means, flow control means for varying the flow of cooling fluid through said cooling means, control means for varying the capacity of said cooling fluid supplying means, thermostatic means for controlling both of said control means in a manner to substantially simultaneously vary the flow of cooling medium and the capacity of said cooling fluid supplying means, and humidity responsive means for cooperating with said thermostatic means in controlling the flow control means only.

11. In an air conditioning system, the combination comprising, cooling means for cooling a space, means for conducting cooling fluid to said cooling means, means for reducing the temperature of the cooling fluid comprising means for varying the volumetric output of the said cooling fluid temperature reducing means, means for controlling the flow of cooling fluid into said cooling means, temperature responsive means for controlling said temperature reducing means and said flow control means to correspondingly vary both the volumetric output of said temperature reducing means and the flow of cooling fluid admitted to the said cooling means upon variation in temperature, in a manner to maintain the temperature of the cooling fluid substantially constant irrespective of demand upon the temperature reducing means caused by variation in flow, and humidity responsive means for increasing the flow of cooling fluid admitted to said cooling means upon a decrease in humidity without correspondingly varying the volumetric output of the said cooling fluid temperature reducing means.

12. In an air conditioning system, the combination comprising, a conditioning chamber, means connecting said conditioning chamber with a space to be conditioned, cooling means in said chamber for removing heat from the air as it passes through said chamber, means for conducting cooling fluid to said cooling means, means for reducing the temperature of the cooling fluid comprising means having a plurality of stages of volumetric output of the said cooling fluid, means for controlling the flow of cooling fluid into said cooling means, temperature responsive means in control of said temperature reducing means and said flow controlling means, said temperature responsive means being arranged to increase the flow of cooling fluid into said cooling means and to correspondingly vary the volumetric output of the said cooling fluid tempera-

ture reducing means in accordance with variations in temperature, and humidity responsive means for increasing the flow of cooling fluid into said cooling means without correspondingly increasing the volumetric output of the said cooling fluid temperature reducing means when the humidity decreases to a predetermined value.

13. In an air conditioning system, the combination comprising, cooling means for cooling a space, said cooling means consisting of a plurality of separate cooling devices, means for conducting cooling fluid to said cooling means, means for reducing the temperature of the cooling fluid comprising means for varying the volumetric output of the cooling fluid temperature reducing means, separate valve means for controlling the flow of cooling fluid into said cooling devices, temperature responsive means for controlling said temperature reducing means and said valve means to correspondingly vary both the volumetric output of said temperature reducing means and the number of cooling devices in operation upon variation in temperature, in a manner to maintain the temperature of the cooling fluid substantially constant irrespective of demand upon the temperature reducing means caused by variation in flow, and humidity responsive means for increasing the flow of cooling fluid admitted to said cooling means upon a decrease in humidity without correspondingly varying the volumetric output of said cooling fluid temperature reducing means.

14. In an air conditioning system, the combination comprising, cooling means for cooling a space, means for conducting cooling fluid to said cooling means, means for reducing the temperature of the cooling fluid comprising means for varying the volumetric output of said cooling fluid temperature reducing means, means for controlling the flow of cooling fluid into said cooling means, a first control means for controlling said temperature reducing means and said flow control means to correspondingly vary both the volumetric output of said temperature reducing means and the flow of cooling fluid admitted to said cooling means, in a manner to maintain the temperature of the cooling fluid substantially constant irrespective of demand upon the temperature reducing means caused by variation in flow, and a second control means for increasing the flow of cooling fluid admitted to said cooling means without correspondingly varying the volumetric output of said cooling fluid temperature reducing means.

15. In an air conditioning system, the combination comprising, cooling means for cooling a space, means for conducting cooling fluid to said cooling means, means for reducing the temperature of the cooling fluid comprising means for varying the volumetric output of said cooling fluid temperature reducing means, means for controlling the flow of cooling fluid into said cooling means, a first control means for controlling said temperature reducing means and said flow control means to correspondingly vary both the volumetric output of said temperature reducing means and the flow of cooling fluid admitted to said cooling means, in a manner to maintain the temperature of the cooling fluid substantially constant irrespective of demand upon the temperature reducing means caused by variation in flow, a second control means for increasing the flow of cooling fluid admitted to said cooling means without correspondingly varying the volumetric output of said cooling fluid tem-

perature reducing means, temperature responsive means and humidity responsive means, one of said responsive means controlling said first control means and the other of said responsive means controlling said second control means.

16. In air cooling and dehumidifying apparatus, the combination of evaporator means, means for effecting flow of a stream of air over said evaporator means, variable capacity compressor means, means operable automatically to initiate and terminate operation of the compressor in response to increase above and decrease below a predetermined temperature of air, means for automatically increasing and decreasing both the portion of the evaporator means containing liquid refrigerant and the rate of fluid translation (by volume) of said compressor means in response to increase and decrease, respectively, in temperature of air, and means operating automatically to increase and decrease the ratio of the rate of fluid translation (by volume) to the liquid containing portion of the evaporator means in response to increase and decrease, respectively, in humidity of air.

17. In air cooling and dehumidifying apparatus, the combination of evaporator means, variable capacity compressor means and a condenser connected in a refrigerant circuit, means operable in response to increase in temperature of air above a first predetermined value for effecting operation of the apparatus with a reduced portion of the evaporator means containing liquid refrigerant and the compressor operating at reduced rate of fluid translation (by volume), means operable in response to increase in humidity of air for increasing the ratio of the rate of fluid translation (by volume) of said compressor means to the liquid containing portion of the evaporator means, and means operable in response to increase in temperature of air above a second and higher predetermined value for increasing the liquid containing portion of the evaporator means independently of humidity.

18. In an air conditioning system, a refrigerating system including compressor means and a plurality of evaporators for removing sensible and latent heat from the air to be conditioned,

means for circulating air in heat exchanging relation with said evaporators and through a space to be conditioned, a valve associated with each evaporator for controlling the flow of refrigerant into said evaporator, a thermostatic controller responsive to the temperature in a space being conditioned and movable between different controlling positions, means responsive to the humidity in said space and means operatively connecting said thermostatic controller and said humidity responsive means to said valves and operative to cause opening of the valves to all of said evaporators when the thermostatic controller is in a predetermined high temperature position, and to cause opening of less than all of said valves when the space humidity rises to a predetermined value and the thermostatic means assumes a lower temperature position.

19. In an air conditioning system, a refrigerating system including compressor means and a plurality of evaporators for removing sensible and latent heat from the air to be conditioned, means for circulating air in heat exchanging relation with said evaporators and through a space to be conditioned, a valve associated with each evaporator for controlling the flow of refrigerant into said evaporator, a thermostatic controller responsive to the temperature in a space being conditioned and movable between different controlling positions, means responsive to the humidity in said space and means operatively connecting said thermostatic controller and said humidity responsive means to said valves and operative to cause closure of the valves to all of said evaporators when said space temperature and said humidity are both low, to cause opening of the valves to all of said evaporators when the thermostatic controller is in a predetermined high temperature position, and to cause opening of less than all of said valves when the space humidity rises to a predetermined value and the thermostatic means assumes a lower temperature position.

GEORGE D. GULER.
